HYDROFLUORIC ACID RESISTANT PACKING MATERIAL

James D. Covington, Dallas, Tex., assignor, by
mesne assignments, to Socony-Vacuum Oil
Company, Incorporated, New York, N. Y., a
corporation of New York

Application July 7, 1944, Serial No. 543,855

2 Claims. (CL 252—29)

1

This invention relates to packing materials, and particularly to packing materials employed in the control units of systems or processes utilizing hydrofluoric acid, particularly to processes for the condensation of hydrocarbons, such as the alkylation of isoparaffins with olefins, the polymerization of olefins, the alkylation of aromatic hydrocarbons with olefins and the like.

A typical application of my invention is its use in a commercial alkylation process, such as the alkylation of isoparaffins such as isobutane with olefins such as the butenes. The invention will be illustrated as applied to an alkylation process of this type. It is to be understood, however, that the principles of my invention are applicable to any process or system wherein essentially anhydrous hydrogen fluoride is utilized as a catalyst or other treating agent and/or wherein control of the flow of this acid or its agitation are required.

Hydrofluoric acid exerts a strong corrosive action on many of the materials normally used in the construction of refinery equipment. Also, the acid is highly toxic and is therefore a potentially hazardous chemical. For these reasons the use of hydrofluoric acid as an alkylation catalyst has introduced new problems in design, construction and operation of refinery equipment.

A particularly troublesome problem encountered in HF alkylation plants has been the frequent occurrence of leaks in circulating pumps and control valves and the like through which hydrofluoric acid, or mixtures of hydrofluoric acid and hydrocarbons, are conducted in the process. These leaks are caused mainly by deterioration of the packing used in these units due to the action of the hydrofluoric acid, although infrequently, corrosion of the metal parts of such units, after prolonged exposure to the acid, is a contributing factor. These leaks are not only troublesome from an operational standpoint but they constitute a serious hazard to personnel because of the high toxicity of the acid.

It is an object of my invention to provide a novel compacted packing and lubricating material for use in flow control units, such as pumps, valves and the like which are employed in systems carrying hydrofluoric acid, said packing material being highly resistant to the action of hydrofluoric acid, whereby the occurrence of costly and hazardous leaks, due to packing failure in such control units is substantially minimized.

I have discovered that when units such as pumps and valves, which handle hydrofluoric acid or mixtures containing hydrofluoric acid such as in the alkylation of isobutane with butenes,

2

are packed with a packing material comprising talc instead of the conventional packing materials the operating period during which no leakage will occur in such units is greatly increased.

5 In order that a full understanding of the invention and the advantages to be derived from its use may be had, reference is made to the accompanying drawing which is a flow diagram of a conventional process for producing alkylated hydrocarbons from isobutanes and butenes utilizing hydrogen fluoride as a catalyst.

In the drawing there is shown a reaction circuit 1 into which butene feed stock is admitted through line 2 fitted with valve 3. Isobutane feed stock is fed to the reaction circuit through line 4 fitted with valve 5. Essentially anhydrous hydrofluoric acid catalyst is delivered to the reaction circuit through line 6 provided with valve 7 by way of line 8. A circulating pump 10 circulates the reactants and the hydrofluoric acid continuously around the reaction circuit. A cooler 11 is provided in order to maintain the reactants at the desired reaction temperature. The reactants may be by-passed through the cooler 11 in any desired proportion by means of flow regulation valve 12. Material is continuously withdrawn from the circulating mixture through line 13 provided with valve 14 to separator 15 where gravity separation of hydrofluoric acid from reacted and unreacted hydrocarbons occurs, forming an acid phase and a hydrocarbon phase. The heavier acid phase settles to the bottom of the separator 15 and is withdrawn through line 8 provided with valve 16 and recycled to reaction circuit 1 by means of a pump 20. The hydrocarbon phase is withdrawn from the top of separator 15 through line 21 provided with valve 22 and passed to fractionating column 23 provided with reboiler 24. Small amounts of hydrofluoric acid carried over in the effluent stream from the separator 15 may be removed from the process at this point by treatment in a suitable alkaline absorber or by means of a hydrofluoric acid stripper (not shown). Liquid alkylate product is withdrawn from the bottom of fractionator 23 through line 25 fitted with valve 26 while the lighter components of the reacted mixture, comprising unreacted isobutane with small amounts of n-butane and lighter gases such as propane, ethane, etc., formed in the reaction circuit are taken off overhead in line 27. In line 27 the isobutane and normal butane-containing fraction is conducted to fractionator 28 in which the isobutane is separated and recycled to reaction circuit 1 by way of line 29 provided with com-

pressor 30, cooler 31 and valve 32. Normal butane is withdrawn from fractionator 28 in line 33 fitted with valve 34, while the gases lighter than isobutane are vented through line 35.

In the operation of the hydrofluoric acid alkylation process just described trouble has been encountered due to the frequent occurrence of leaks in the hydrofluoric acid recycle stream pump 20 and in the circulating pump 10. Leaks were also encountered, though they were less frequent, in control valves 7, 14 and 16. All of these leaks were the result of deterioration of the conventional packing used in these units. The life of the packing material in the circulating pumps under conditions of continuous operation was only a few hours on the average and rarely exceeded a day after which time leakage occurred and repacking was necessary. However, when in accordance with my invention a packing composition comprising talcum powder was employed in these units leakage was prevented for periods as long as from 3 to 5 weeks under conditions of continuous operation. This represents about a thirtyfold increase in the length of the packing life. The fact that talc is so effective for this purpose is surprising since it is essentially a silicious material ($MgO \cdot 4SiO_2 \cdot H_2O$) and therefore would be expected to be attacked readily by hydrofluoric acid. Whether a reaction does occur between the talc and the hydrogen fluoride to produce a substance which affords the talc its effectiveness as a packing in the presence of hydrogen fluoride is not known to me, the evident fact being that it is so effective.

In order to reduce friction and afford a lubricating quality to the talc, I generally mix the talc with flake graphite. I have found that best results are obtained by using a mixture of talc and graphite containing from about 10 to about 25 percent by weight of graphite although mixtures containing as high as 50 percent may be employed.

Though I have described and illustrated my invention in connection with an alkylation process, it should be understood that the principle of the invention is equally applicable to other hydrofluoric acid processes or to systems carrying hydrofluoric acid or mixtures thereof in which circulating pumps, agitators and stirrers having packed shafts, bearings, etc., are exposed to hydrogen fluoride.

By the terms "hydrofluoric acid" and "essentially anhydrous hydrogen fluoride" as used throughout this specification and in the appended claims I refer to hydrogen fluoride diluted with or containing not more than 10% of water.

Having now fully described my invention what I claim as new and wish to be secured by Letters Patent is:

1. As a new article of manufacture, a compacted packing and lubricating mass consisting of an intimate mixture of talc and flake graphite, said mass characterized by being highly resistant to the action of hydrogen fluoride and the talc being present in an amount from about 75 to about 90 per cent of the total weight of the mixture.

2. As a new article of manufacture a compacted packing and lubricating mass characterized by being highly resistant to the action of hydrogen fluoride consisting of an intimate mixture of talc and flake graphite in which the talc comprises from 50 to about 90% by weight of the mixture.

JAMES D. COVINGTON.
